UNITED STATES PATENT OFFICE.

RUDOLF ZÖLLNER, OF DRESDEN, GERMANY.

CONNECTION TERMINAL.

Application filed April 6, 1921. Serial No. 459,198.

To all whom it may concern:

Be it known that I, RUDOLF ZÖLLNER, a citizen of the German Republic, and residing at Dresden, Germany, have invented certain new and useful Improvements in Connection Terminals, of which the following is a specification:

This invention relates to an improved connection-terminal for electric conductors, which has essential advantages: 1, it ensures an absolute safe and permanent contact of the conductors to be connected; 2, the conductors can be easily and quickly attached thereto, whereby time is saved; 3, any screws and thus damage by the same to the conductors to be connected are omitted; 4, it is absolutely reliable, even when used in connection with vibrating conductors, any faults in the connection of the conductors causing a heating of the latter or a flickering of the light being thereby dispensed with.

In the accompanying drawing:

Fig. 1 is a plan view of a distribution-block (with removed cover) containing a plurality of the improved connection-terminals;

Fig. 2 is a perspective view of such a distribution-block with cover;

Figs. 3, 4, 5, and 6 show the single parts of the improved connection-terminal in perspective views;

Figs. 7 and 8 are partially sectional side views, at right angles to one another, showing the improved connection-terminal in its position of use.

The distribution block comprises a porcelain base α having holes β for a passage of the electric conductors therethrough and a plurality of connection-terminals attached thereto, the same being covered as shown at c .

The connection-terminal comprises a stirrup d having parallel side members, a closed head, and lower outwardly extending feet e ; a coil spring g ; a washer h having two notches i therein forming a tongue k between them; and a cap l with downwardly extending rim m having two similar notches n therein forming a tongue o between them.

Said stirrup d is inserted in said porcelain base α from below through a hole therein, that is widened at its lower part for the reception of the feet e , which thus bear against the step formed by said lower widen-

ing, the hole being filled-out with cement f whereby the stirrup d is firmly fixed in position.

Thereupon, the coil-spring g is mounted over said stirrup d , the lower end of said coil-spring bearing then upon the top of the porcelain base α , which is preferably recessed for a safe reception of the same. The washer h is then so placed upon the upper end of said coil-spring that it engages with its notches i over the side members of said stirrup d , its tongue k engaging then in the space between said side members. Finally, the cap l is placed over said washer in such a way that its notches n engage also over the side members of the stirrup d and its tongue o in the space between said side members, but from the opposite side thereof, so that the side members are embraced from both sides.

With empty connection-terminal, the cap l is allowed to move, by action of said coil-spring g , in upward direction until its tongue o strikes against the underside of the closed head of the stirrup d .

For intended use of the connection-terminal, the cap l is depressed against the action of the coil-spring g , the blank ends of the electric conductors to be connected being then shifted from opposite sides into the space beneath the closed head of the stirrup d , and the cap l is released, whereupon the connection intended is completed.

What I claim, is:

A connection-terminal comprising a fixed stirrup having outwardly extending feet, parallel side members and a closed head, a coil-spring located over said stirrup, a washer placed upon the upper end of said coil-spring and having two notches forming a tongue between them, and a cap placed over said washer and having two similar notches forming a tongue between them, said washer and cap embracing the side members of said stirrup from opposite sides, substantially as and for the purpose set forth.

In testimony whereof I have hereunto set my hand in the presence of two subscribing witnesses.

RUDOLF ZÖLLNER.
